UNITED STATES PATENT OFFICE.

WILLARD F. RICHARDS, OF BUFFALO, NEW YORK, ASSIGNOR TO GOULD COUPLER COMPANY, OF NEW YORK, N. Y., A CORPORATION OF WEST VIRGINIA.

DRAW-BAR ATTACHMENT FOR LOCOMOTIVES.

SPECIFICATION forming part of Letters Patent No. 700,982, dated May 27, 1902.

Application filed November 21, 1901. Serial No. 83,176. (No model.)

To all whom it may concern:

Be it known that I, WILLARD F. RICHARDS, a citizen of the United States, residing at Buffalo, in the county of Erie and State of New 5 York, have invented new and useful Improvements in Draw-Bar Attachments for Locomotives, of which the following is a specification.

This invention relates more particularly to a draw-bar attachment intended for locomotives, in which the draw-bar is pivoted to swing laterally and is provided with side springs which yieldingly retain the draw-bar in its central position and permit the same to swing laterally to either side of said central position 10 to accommodate itself to the position of the locomotive and allow of couplings on curves. In such draw-bar attachments of which I am aware coiled springs are usually arranged at the opposite sides of the draw-bar, and the 15 lateral movement of the draw-bar is determined by the length of the spring or springs at each side thereof, thus requiring unusually long springs where a considerable lateral movement of the draw-bar is necessary or desired.

The main object of the invention is to provide a draw-bar attachment especially designed for locomotive-pilots in which the draw-bar is permitted a greater lateral movement than heretofore without necessitating the employment of springs of increased length.

In the accompanying drawings, consisting of three sheets, Figure 1 is a longitudinal vertical sectional elevation of a locomotive-pilot and draw-bar attachment, illustrating my invention. Fig. 2 is a plan view of the same. Fig. 3 is a transverse sectional view on the line 3 3, Fig. 1, on an enlarged scale. Fig. 4 is a fragmentary sectional view on the 35 line 4 4, Fig. 3. Fig. 5 is a similar view on line 5 5, Fig. 3. Fig. 6 is a front elevation, partly broken, of the pilot and draw-bar attachments, showing the draw-bar in its side position. Fig. 7 is a plan view thereof, showing the draw-bar in the position indicated in Fig. 6.

Like letters of reference refer to like parts in the several figures.

Referring to the drawings, A represents a locomotive-pilot, and B the locomotive end 50 sill which carries the pilot.

C represents the coupler, and C' the draw-bar or stem therefor, which is arranged beneath the end sill and extends forwardly and rearwardly thereof, being pivoted at its rear 55 end in any suitable manner to a bracket D, secured to the rear face of the end sill, so as to permit the forward end of the draw-bar to have an extended swing or movement.

E indicates a combined support and guide-box for the forward end of the draw-bar. This box is preferably in the form of a casting having a top horizontal transverse member e and lower separated front and rear guideways or flanges e'. The guide-box is 60 supported in any approved manner from the pilot, for which purpose it is shown as being provided with a centrally-disposed depending stem or post F, which is located between and secured to separated plates or bars f, rising 70 from the lower front end of the pilot and secured at their upper ends to the lower horizontal side of a substantially U-shaped bracket f', the upper ends of the sides or legs of which are secured to the front face of the pilot-beam 75 f''. Lateral stays or beams G, secured to the ends of the box, as at g, and to opposite or outer ends of the pilot-beam, add to the rigidity of the attachment. The forward end of the draw-bar projects forwardly through said 80 U-shaped bracket f' and is supported and guided between the upper transverse member e and the lower guideways e' of the box and rests on the latter.

H represent oppositely-arranged spring-pockets, each of which is provided with front and rear horizontal flanges or ribs h, which engage on the guides e' of the guide-box and are thereby guided and permitted to slide laterally. Each spring-pocket is provided 85 with an upwardly-extending lug or portion h', constituting an abutment, the abutments of the opposite spring-pockets being arranged on opposite sides of the draw-bar and engaged by the latter. The upper portion of 90 the depending post F is provided with oppo-

site depressions or recesses *j* for receiving the inner ends of the spring-pockets in order to permit them to come near together.

k represents a stop lug or projection arranged centrally of the post between said depressions *j* for the purpose of limiting the inward movement of the spring-pockets.

L L' represent oppositely-arranged coiled springs, each having its inner end seated in the socket *h*² of the spring-pockets, and M represents a rod or bar, which passes through aligned openings in the sockets *h*² of the spring-pockets and in the abutment *k* and also through the oppositely-arranged coiled springs L L'. Each end of the rod or bar M is provided with a nut or the like, which engages the outer end of the adjacent coiled spring and confines the same between said nut or the like and its spring-pocket.

20 When the draw-bar is swung to one side of its central position—for instance, to the right, as shown in Figs. 6 and 7—it engages the abutment on the right-hand spring-pocket and shoves the latter and its spring along in 25 its guideways *e'*. The other spring-pocket is held from movement to the right by reason of its engagement with the stop *k*; but the rod or bar M is forced by the right-hand spring together with the pocket, and inasmuch as this movement of the rod is opposed 30 by the left-hand spring both springs are compressed to their limit before the movement of the right-hand spring-pocket and the draw-bar is arrested. It will thus be seen that the 35 draw-bar can move from the central portion a distance substantially twice as great as would be permitted if the springs were mounted in a fixed position. The draw-bar can of course move to the other side of the central 40 position an equal distance, as will be obvious.

I claim as my invention—

1. The combination with a locomotive-pilot, of a guide-box supported by said pilot, a draw-bar mounted to move laterally and having its 45 forward end guided by said box, spring-pockets slidably mounted on said box, oppositely-arranged springs carried by said pockets, a stop between said pockets, and a rod or bar connected at its opposite ends to the outer 50 ends of said springs and movable relative to said spring-pockets substantially as set forth.

2. The combination with a locomotive-pilot, and a draw-bar mounted to swing laterally, of a guide and supporting box for the forward 55 end of said draw-bar attached to said pilot, guides on said box, oppositely -arranged spring -pockets slidably mounted in said guides, an abutment or stop between said spring -pockets, oppositely -arranged coiled 60 springs seated in sockets in the outer sides of said spring -pockets, a rod or bar passing through said coiled springs and through openings in said spring-pockets, and stops or abutments at the opposite ends of said rod or bar 65 engaging the outer ends of said coiled springs, substantially as set forth.

3. The combination with a locomotive-pilot and a draw-bar mounted to swing laterally, of a guide and supporting box secured to said 70 pilot and having separated guides and a centrally-disposed depending post or standard secured to the pilot, spring-pockets slidably mounted in said guides and having upwardly-projecting abutments arranged on opposite 75 sides of said draw-bar and in their outer sides with sockets, a stop or abutment on said depending post between said spring-pockets, oppositely -arranged coiled springs having their inner ends seated in said sockets, and 80 a rod or bar passing through openings in said spring -pockets and through said coiled springs, and stops or abutments at the opposite ends of said rod or bar engaging the outer ends of said coiled springs, substantially 85 as set forth.

4. The combination with a locomotive-pilot, and a draw-bar mounted thereon to move laterally, of a guide-box for said draw-bar having a depending post, plates or bars rising 90 from the lower part of said pilot to which said post is secured, a substantially U-shaped bracket arranged in rear of said guide-box and secured at its upper end to the upper part of said pilot and at its lower end to said 95 plates or bars, said draw-bar passing between the arms of said bracket and through said guide-box, substantially as set forth.

Witness my hand this 30th day of October, 1901.

WILLARD F. RICHARDS.
